(57) **CLAIM**

The ornamental design for a front panel for electronic cabinet, as shown and described.

DESCRIPTION

FIG. 1 is a perspective view of a front panel for electronic cabinet according to our new design;

FIG. 2 is a front view thereof;

FIG. 3 is a right side view thereof;

FIG. 4 is a left side view thereof; and,

FIG. 5 is a top view thereof, the bottom view being a mirror image of the top view.

The broken line showing of environmental structure and boundaries in FIGS. 1-5 is for illustrative purposes only and forms no part of the claimed design.

1 Claim, 2 Drawing Sheets

FIG. 4

FIG. 2

FIG. 5
